Primary Examiner — Mitchell I. Siegel(74) Attorney, Agent, or Firm — Randy K. ChangCLAIM

The ornamental design for striking face for a golf club head, as shown and described.

DESCRIPTION

The SOLE FIGURE here is a front elevational view of a striking face for a golf club head showing my new design. The broken line showing the striking face and golf club head is included for the purpose of illustrating unclaimed subject matter and forms no part of the claimed design.

1 Claim, 1 Drawing Sheet(56)
